UNITED STATES PATENT OFFICE.

DUKE GUICE, HERMAN PERRY DOHRMEIER, AND OSCAR ALEXANDER LANE, OF GREENVILLE, ALABAMA.

FOLDING CRATE OR BOX.

1,129,088.

Specification of Letters Patent.

Patented Feb. 23, 1915.

Application filed September 3, 1913, Serial No. 787,880. Renewed January 9, 1915. Serial No. 1,453.

To all whom it may concern:

Be it known that we, DUKE GUICE, HERMAN P. DOHRMEIER, and OSCAR A. LANE, citizens of the United States, residing at 5 Greenville, in the county of Butler and State of Alabama, have invented certain new and useful Improvements in Folding Crates or Boxes, of which the following is a specification.

10 This invention relates to improvements in foldable or collapsible crates or boxes.

An important object of this invention is to provide a crate or box of the above mentioned character, which is so constructed 15 that proper ventilation is afforded to the goods stored therein, at all times, irrespective of the position that the crate or box may occupy, that is, whether it is stood on either end or laid upon either side.

20 A further object of the invention is to provide a crate of the above mentioned character, which is so constructed that the same may be shipped from the factory or place of manufacture in a partly assembled condition 25 with the parts thereof lying flat, to occupy the minimum amount of space for shipment, such partly assembled condition aiding the user in readily completely assembling the same.

30 A further object of the invention is to provide novel means for tying or binding together the several parts of the crate or box.

A further object of the invention is to 35 provide a crate or box of the above mentioned character, which is light, strong, durable, cheap to manufacture, and convenient in use.

Other objects and advantages of this invention will be apparent during the course 40 of the following description.

In the accompanying drawings forming a part of this specification and in which like numerals are employed to designate like parts throughout the same, Figure 1 is a side 45 elevation of a crate or box embodying the invention, Fig. 2 is an end elevation of the same, Fig. 3 is a plan view of the same, Fig. 4 is a perspective view of the top piece or cover, Fig. 5 is a similar view of the 50 connected end and side pieces, the same being collapsed or folded, and, Fig. 6 is a similar view of a bottom piece.

In the drawings, wherein is illustrated a preferred embodiment of the invention, the numeral 7 designates oppositely arranged 55 side pieces, which are identical, each comprising longitudinally extending horizontal rods or bars 8, having vertical spaced veneers or strips 9, disposed upon the inner sides thereof and attached thereto by means 60 of nails 10 or the like. Attention is called to the fact that the rods or bars 8 extend outwardly beyond the veneers or strips 9 and are provided near their free ends with openings or apertures 11, as shown in Fig. 3. 65

The numeral 12 designates end pieces, comprising upper and lower horizontal transverse rods or bars 13, upon the inner sides of which are mounted vertical spaced veneers or strips 14, attached thereto by 70 means of nails 15 or the like. The lower rod or bar 13 is disposed adjacent to or flush with the lower ends of the veneers or strips 14, while the upper rod or bar 13 is disposed near and spaced from the upper ends 75 of the veneers or strips 14. As clearly shown, the end rods or bars 13, are disposed adjacent and between the side rods or bars 8, the end rods or bars 13 being provided with openings or apertures 16, adapted for 80 registration with the apertures 11 of the side rods or bars 8.

The numeral 17 designates three separate vertical binding wires, provided at their lower ends with stop-heads 18. These wires 85 are threaded or passed through the openings 11 and 16 of the side and end rods or bars 8 and 13, before the same are shipped from the factory, whereby the side and end pieces are pivotally connected at three points, 90 forming in effect a flexible construction adapted to be collapsed, to occupy a flat position, as clearly shown in Fig. 5. When the end and side pieces are thus collapsed, the strips or veneers attached to the rods or bars 95 are arranged outermost. When assembling the crate or box, the side and end pieces are swung around so that the rods or bars are arranged upon the outer side of the strips or veneers. When the crate or box is assembled there is a fourth vertical binding wire 18', which is identical with the outer binding wires 17, but which is not threaded or passed through the openings 11 and 16, of

the rods or bars, until the end and side pieces are brought to their assembled or operative position, as shown.

As more clearly shown in Figs. 1 and 6, 5 the numeral 19 designates a bottom piece, formed of longitudinally extending transversely spaced veneers or strips 20, mounted upon transverse supporting rods or bars 21, arranged adjacent the ends thereof and attached thereto by any suitable means. In 10 the assembled condition of the crate or box, the bottom 19 is arranged within the lower portion of the same, with the opposite ends of the transverse supporting rods or bars 21 resting upon the longitudinal side rods or 15 bars 8, as more clearly shown in Fig. 1.

As more clearly shown in Figs. 3 and 4, 20 the numeral 22 designates a top piece or lid, comprising transverse spaced veneers or strips 23, upon the outer sides of which are arranged longitudinally extending rods or bars 24, spaced from the ends of the strips or veneers and attached thereto by any suitable means. At their opposite ends, the 25 longitudinal rods or bars 24 extend beyond the transverse strips or veneers 23 and are provided adjacent such opposite ends with inwardly spaced recesses or notches 25, as shown. When the box is assembled, the top 30 piece or lid 22 is arranged upon the end and side pieces, as more clearly shown in Fig. 3, the transverse veneers or strips 23 engaging the side longitudinal rods or bars 8, the rods or bars 24 extending longitudinally of the 35 crate or box inwardly of and spaced from the longitudinal rods or bars 8, as clearly shown in Fig. 3. The upper ends of the binding wires 17 and 18 are first bent inwardly to pass within the vertical recesses 40 or notches 25 and then outwardly and downwardly, forming loops 26, the downwardly extending portions 27 of the binding wires passing exteriorly of the transverse end rods or bars 13, and being connected with the 45 binding wires by being twisted about the same, as shown at 28. In this manner the side, end and top pieces are securely bound together rendering it impossible for them to accidentally or improperly separate, but 50 allowing for the same being readily separated when desired.

Any holding means may be arranged within the crate or box depending upon the articles to be shipped. The crate or box is 55 well adapted for holding fruit or vegetable boxes or baskets. There may be a horizontal partition between the layers of boxes or baskets, if desired.

It is to be understood that the form of 60 our invention herewith shown and described is to be taken as a preferred example of the same, and that various changes in the shape, size and arrangement of parts may be re-

sorted to without departing from the spirit of the invention or the scope of the sub- 65 joined claims.

Having described our invention, we claim:

1. A box or crate of the character described, comprising side and end pieces embodying longitudinally extending bars projecting at their opposite ends beyond the same for a substantial distance and apertured, the apertured ends of the bars in one set being adapted to cross the apertured ends of the bars in the other set, binding wires, at least one of which is removable, passed through the overlapping apertured ends of the bars at the corners of the box or crate and provided at their lower ends with means 80 to prevent the upward movement of the same with relation to such apertured overlapping ends, such binding wires serving to pivotally connect the apertured overlapping ends and extending at their upper ends a 85 substantial distance above and beyond the upper apertured overlapping ends, a bottom piece to close the lower end of the box or crate, and a top adapted to be arranged upon and engage with the side and end 90 pieces and embodying spaced bars extending at opposite ends beyond the same for a substantial distance, the upper free ends of the binding wires being adapted to be bent about the ends of the top bars and then downwardly for a substantial distance and wound about the body portion of the binding wires. 95

2. A box or crate of the character described, comprising, in combination, side and end pieces embodying upper and lower longitudinally extending bars projecting at their opposite ends beyond the same for a substantial distance and apertured near such opposite ends, the apertured ends of the bars in one set being adapted to cross the apertured ends of the bars in the other set, binding wires, at least one of which is removable, passed through the overlapping apertured ends of the bars at the corners of the box or crate and provided with means to prevent their upward movement with relation to such apertured overlapping ends, such binding wires serving to pivotally connect the apertured overlapping ends and extending at their upper ends for a substantial distance above and beyond the upper apertured overlapping ends, a bottom piece to close the lower end of the box or crate, and a top adapted to be arranged upon and engage with the side and end pieces and embodying longitudinally extending exteriorly arranged bars disposed inwardly of and spaced a substantial distance from the ends of the bars of the end pieces and projecting at their opposite ends beyond the top for a substantial distance and provided at such ends upon 110 115 120 125

their inner longitudinal sides with vertical grooves, the upper free ends of the binding wires being adapted to be passed first beneath the protruding ends of the top bars and upwardly through the vertical grooves and bent downwardly around such protruding ends and then carried downwardly for a substantial distance and wound about the body portion of the binding wires.

In testimony whereof we affix our signatures in presence of two witnesses.

DUKE GUICE.
HERMAN PERRY DOHRMEIER.
OSCAR A. LANE.
